UNITED STATES PATENT OFFICE.

CARLETON ELLIS, OF MONTCLAIR, NEW JERSEY, ASSIGNOR TO ELLIS-FOSTER COMPANY,
A CORPORATION OF NEW JERSEY.

TREATING OILS.

1,249,278.

Specification of Letters Patent. Patented Dec. 4, 1917.

Application filed April 29, 1913. Serial No. 764,323.

To all whom it may concern:

Be it known that I, CARLETON ELLIS, a citizen of the United States, and a resident of Montclair, in the county of Essex and State of New Jersey, have invented certain new and useful Improvements in Treating Oils, of which the following is a specification.

This invention relates to a process of making lighter from heavier oil petroleum products and relates in particular to the production of gasolene from kerosene or other heavier oils by heat decomposition under conditions which enable the production of a substantial or maximum yield of light spirit by virtue of such operation.

Reference is had to the accompanying drawings in illustration of the process and apparatus of the present invention, these drawings representing the preferred embodiment from which various modifications and deviations are feasible as will be evident to those skilled in the art after inspection hereof.

In the drawings Figure 1 shows in diagrammatic fashion a tubular heating system and condensing apparatus which are depicted partly in vertical section and partly in elevation. Fig. 2 shows a form of heating element.

In the drawings 1 is a chamber preferably of considerable height having inlets 2 for the admission of hot gasses or products of combustion or inflammable gas for heating purposes. At the top of the chamber are outlets 3 which, of course, may be if desired connected with a suitable stack. In the chamber 1 are arranged a series of nearly horizontal pipes 4 which, however, as shown preferably have a slight inclination so as to zigzag across the chamber from top to bottom, the lower tube of the series being preferably less inclined than the other tubes. 5 is an inlet pipe for kerosene or other oil used for the present purpose, this pipe being provided with the valve 6. Through this pipe also may be fed water or aqueous solution (a diluted solution of ammonium nitrate may be used) or suitable catalytic material in solution. The pipe 5 as will be noted communicates with the uppermost pipe of the aforesaid series 4. The lowermost pipe of the series 4 has an outlet 7 controlled by the valve 8. The several pipes or tubes are connected by means of the headers

9 in which are placed plugs 10 which enable the tubes to be opened and viewed from end to end, or readily cleaned as occasion requires. The second series of tubes is indicated by 11. These tubes form a rising system leading from the lowermost tube of series 4 and are connected one with another in a manner similar to the series 4. Preferably the series 11 is given a greater inclination than the series 4 and preferably the uppermost tube of series 11 is below the uppermost tube or tubes of series 4. The uppermost tube of series 11 communicates with a riser 12 connected with an air condenser 13, one member of which yields its condensation products to the pipe 14 which passes through a condenser trough 15 filled with water and connects with the trap 16 which is fitted with the draw-off 17. The riser 20 provided with a valve allows of the separation of gas and uncondensable products which may be separately collected. From the trap 16, the pipe 18 equipped with the valve 19, leads to the uppermost pipe of the tubular heating series 4. A pump 27 may be interposed in this pipe to facilitate the removal of the liquid products from pipe 14 and trap, 16 especially when the tubular system is operating under pressure. A second wing or member of the air condenser 21 serves for the condensation of lighter products more particularly the gasolenes which pass through the condensing pipe 22 going thence to the trap 23 having the draw-off 24 from which gasolene or similar light products may be withdrawn. 25 is a gas venting pipe having the valve 26. Although the air condensing members 13 and 21 are but two in number as here shown it will be evident that the number may be increased to provide for the separation of several fractions as desired. The size of the air condenser should be proportioned with respect to the output of vapors from the heating chamber 1.

The function of the rising tubular series 11 is mainly that of digestion and final reaction which ordinarily does not require an extremely elevated temperature, but is in substance a time reaction involving rearrangement of molecules to establish substantial or ultimate equilibrium of the components of the resulting gasolene whereby such product is stabilized. It is to be under-

stood that the term "equilibrium" as here employed has reference to the molecular condition of the components of the gasoline resulting from the reactions effected during 5 the digestion of the products of the heat decomposition of the material treated, in which reactions unsaturated or otherwise unstable bodies produced, act by chemical union with the gases, and particularly hydrogen, produced 10 by such decomposition or by union with each other or by polymerization, to produce saturated or otherwise substantially stable compounds whereby the gasoline is stabilized. Such digestive function, as it 15 may perhaps be termed, may obtain in the apparatus 30 and the tubular heating series 11 may be dispensed with, this being done in the apparatus shown, by inserting the plug in the lower end of the lower member of the 20 series 11 so far as to prevent the flow of vapors through said series. The pipe 7 has a draw-off 28. An extension 29 of the pipe 7 enters the apparatus 30 and connects with the riser 31 which in turn communicates 25 with the digestion chambers 32. These digestion chambers are preferably of considerable length and width, but of a relatively small height, and connected one with another by means of the pipes 33. The digestion 30 chambers are embedded in heat insulating material so that radiation loss is reduced.

It will be evident that chambers of various shapes and forms may be employed instead 35 of those set forth herein so long as they serve the function of the chambers 32. The tubes of the series 4 preferably are filled with suitable catalytic material 4' which also may be the case with the rising series 11, al- 40 though the uppermost of these are sometimes left open but the lower tubes thereof often may carry suitable catalytic material to ad- vantage. In order to secure a greater heat 45 conductivity, especially when the pipes or tubes are large in size, nickel, iron or steel balls, disks or irregular shaped metal frag- ments and the like may be used more or less throughout the tubular system in order to secure a more rapid decomposition and 50 transfer of heat and some or all of the pipes may be equipped with fins as shown in the lowermost tube of the heating series 4.

It is one consideration of the present in- 55 vention to secure a high heating efficiency from the fuel used in the apparatus and to this end a regenerative effect is secured by building the apparatus 1 of considerable height, or when the same principles of construction are carried out with a horizontal 60 heater, then such heater should be of con- siderable length in order to secure a regen- erative effect due to the cold or relatively cool charge entering the uppermost pipe 4 and passing down to a hotter zone so that 65 the hottest flame or products of combustion

come in contact with the lowermost tubes which thus are kept hottest; while the spent products of combustion pass upwardly in contact with the cooled tubes in the upper portion of the heat chamber 1 where the 70 last available heat values may be largely absorbed and utilized.

The tubular rising series 11 in contrast with the descending series 4 extends from the zone of high temperature into one of relatively low temperature so that while the flow of the material along the series 4 is into zones of higher and higher temperature that of the material in the series 11 is into zones of lower and lower temperature, so that 75 while series 4 is functioning as a decomposi- 80 tion system, the rising series 11 serves more as a digesting and equilibrium effecting system, an effect which may be secured to a greater or less degree, according to circum- 85 stances, by the digesting boxes 32. The heat decomposition of petroleum oil normally gives rise to various unsaturated products and the gasoline resulting from treatment of this character is unstable. By allowing 90 the constituents of the materials formed by reaction to digest in the space afforded a satisfactory quality of gasoline is obtained.

It should, of course, be understood that the production of gasoline from kerosene or 95 other fraction of petroleum, or for that matter from crude oil and various distillates, involves a splitting up of heavy molecules 100 into molecules of lower molecular weight often with the simultaneous generation of hydrogen and other gases and the produc- 105 tion of carbon, soot and tar. It is important to minimize the production of coke, soot and tar as these block the heating pipes more or less and when a catalyst is used 110 are liable to coat the surface thereof and impair its efficiency. The hydrogen which is set free by the decomposition should be given an opportunity to recombine which is entirely possible in view of the fact that un- 115 saturated bodies are produced during the splitting operation. When water is intro- 120 duced into the apparatus the steam reacts in the hotter zone under certain conditions yielding its hydrogen in an available form which is useful. The oil and the water, in case the latter is used, may be delivered to the apparatus in the form of vapor if de- 125 sired.

Preferably I adjust conditions to provide 120 a temperature for the escaping gases leaving the heating chamber 1 that shall range between 150° C. and 250° C. In the lower portion of the heating apparatus I prefer a temperature several hundred degrees higher, 125 preferably between 400° C. and 600° C., de- pending on the oil employed. For kerosene boiling from about 150° C. upward, a tem- 130 perature of about 500° C. in the lower sec- tions is recommended. Heavy fractions

which require high temperatures to decompose may be superheated to 600 or 800° C. or so in the lower heating tubes and may then pass upward through risers 11 into 5 zones of progressively decreasing temperature while equilibrium is being established, or may be passed into digesting chambers 32 for like purposes.

The oil products under treatment are vaporized in the system of tubes 4 between the upper and lower tubes, the point at which vaporization begins and is completed depending upon the temperatures maintained in the heating chamber 1. The temperatures 10 herein indicated for the preferred treatment of kerosene and heavier fractions effect their vaporization at a position or positions in the system such that the resulting vapors travel for a substantial distance through a zone of 15 progressively increasing temperature and the temperatures indicated are preferred both for effecting the heat decomposition of the materials specified and for stabilizing by 20 digestion as hereinbefore described, the resulting lighter products, the rate of flow of 25 the liquid through the upper portion of the system of tubes 4 and vapors through the lower portion of such system and through tubes 11 depending upon the particular material 30 under treatment, such rate of flow being controlled according to the experience of the operator with the particular material under treatment as will be understood by those skilled in the art.

35 By this method of treatment 50 to 75% of a gasoline or light volatile spirit boiling below 150° C. is obtainable from the raw oil material taken, the residue being both gas and other heavy oil products which pass 40 through the system several times without being broken down at the temperatures employed, because of their peculiar resistance to heat. Or in the case of some oils, the final products should be 75° or higher of gasoline 45 or light spirit, the remainder of the oil being converted into gas. By carefully regulating the temperature and especially by giving the vapors a sufficiently long exposure to moderate heat, much less gas is 50 produced than where the heat is sudden, violent and excessive. Thus by careful regulation and using preferably oils which have been fractionated fairly closely the amount of gas produced is very small indeed and the 55 bulk of the oil is converted into light spirit.

What I claim is:

1. The process of making gasoline-like material which comprises passing the vapors of an oil containing essentially petroleum 60 products heavier than gasoline through an elongated zone of progressively increasing temperature maintained at or above the decomposing temperature and in thereafter subjecting the products of such decomposition to a progressively decreasing tempera-

ture without substantial and material condensation until equilibrium of the unstable components of such products is established.

2. The process of making gasoline-like material which comprises passing the vapors 70 of an oil containing essentially petroleum products heavier than gasoline through a zone of progressively increasing temperature maintained at or above the decomposing temperature and in thereafter subjecting the 75 products of such decomposition to a progressively decreasing temperature without substantial and material condensation until equilibrium of the unstable components of such products is established.

3. The process of making gasoline-like material which comprises passing the vapors of an oil containing essentially petroleum products heavier than gasoline through an elongated catalyzing zone of progressively 85 increasing temperature maintained at or above the decomposing temperature and in thereafter subjecting the products of such decomposition to a progressively decreasing temperature without substantial and material condensation until equilibrium of the 90 unstable components of such products is established.

4. The process of making gasoline-like material which comprises passing the vapors 95 of an oil containing essentially petroleum products heavier than gasoline through an elongated zone of progressively increasing temperature maintained at or above the decomposing temperature and in thereafter subjecting the products of such decomposition as vapors to a progressively decreasing temperature in the presence of catalytic material until equilibrium of the unstable components of such products is established.

5. The process of making gasoline-like material which comprises passing the vapors of an oil containing essentially petroleum products heavier than gasoline through an elongated zone of progressively increasing 100 temperature maintained at or above the decomposing temperature and in thereafter subjecting the products of such decomposition as vapors to a progressively decreasing temperature until equilibrium of the unstable components of such products is established.

6. The process of making gasoline-like material which comprises passing the vapors of an oil containing essentially petroleum products heavier than gasoline through a 110 zone of progressively increasing temperature maintained at or above the decomposing temperature and in thereafter subjecting the products of such decomposition as vapors to a progressively decreasing temperature until equilibrium of the unstable components of such products is established.

of such products is established in then condensing said products, substantially freeing same from gas and returning the heavier-than-gasolene components to decomposing zone.

7. The process of making gasolene-like material which comprises passing the vapors of an oil containing essentially petroleum products heavier than gasolene through an elongated catalyzing zone of progressively increasing temperature maintained at or above the decomposing temperature and in thereafter subjecting the products of such decomposition as vapors to a progressively decreasing temperature until equilibrium of the unstable components of such products is established in then condensing said products, substantially freeing same from gas and returning the heavier-than-gasolene components to decomposing zone.

8. The process of making gasolene-like material which comprises passing the vapors of an oil containing essentially petroleum products heavier than gasolene through an elongated zone of progressively increasing temperature maintained at or above the decomposing temperature and in thereafter

subjecting the products of such decomposition as vapors to a progressively decreasing temperature in the presence of catalytic material until equilibrium of the unstable components of such products is established in then condensing said products, substantially freeing same from gas and returning the heavier-than-gasolene components to decomposing zone.

9. The process of making gasolene-like material which comprises subjecting the vapors of an oil containing essentially petroleum products heavier than gasolene to a decomposing temperature and subjecting the products of such decomposition to digestion at an elevated temperature but below a decomposing temperature, until substantial equilibrium of the unstable components of said products is established and substantially stable gasolene material is obtained.

Signed at Montclair in the county of Essex and State of New Jersey this 18th day of April A. D. 1913.
